SELF-LOCKING CASHBOX

Harold E. Forester, Chicago, Ill., assignor to
 Johnson Fare Box Company, Chicago, Ill., a
 corporation of Delaware

Application December 18, 1946, Serial No. 716,920

7 Claims. (Cl. 232—15)

1

This invention relates to a cash box for use in check operated machines. More specifically, it relates to a container which is opened as it is inserted in the machine, and held open during the time it is in the machine to receive the coins inserted but is closed incidental to the operation of removing the box.

It has long been a problem in coin collection to prevent unauthorized removal of coins from a collection box by the person who is authorized to remove the box from the vending machine or other coin collecting machine for transportation to an accounting office.

The prior art discloses some boxes which must be opened and inserted in a machine so that a mechanism will close and lock the box as it is withdrawn from the machine. Various methods have been devised by persons intent upon pilfering from these boxes, for either preventing them from closing and locking or for reopening them after they have been mechanically closed.

It is an object of the invention to provide a device of the kind described in which the self-closing box is latched in the machine until it is closed.

Another object of the invention is to provide an apparatus in which the box is locked closed before it is released from the machine.

Yet another object of the invention is to provide a box having several stages of locking to prevent unauthorized reopening after it is once closed.

Still another object of the invention is to provide a mechanism by which the box is closed preparatory to its removal.

A further object of the invention is to provide a mechanism by which the box is closed and locked prior to removal and is held in the machine until it is closed.

These and other objects will become apparent from a study of this specification and the drawings which are attached hereto and form a part hereof, and in which:

Figure 1 is a view of the cash box in the machine with the coin funnel in place.

Figure 2 is an elevation of the locking and closure mechanism, the case being broken away.

Figure 3 is a top or plan view of the mechanism of Figure 2 with the box and receiver broken away to show the parts in the reset position.

Figure 4 is a view similar to Figure 3 but showing the parts in the coin receiving position with the coin box latched in place.

Figure 5 is a view similar to Figures 3 and 4

showing the parts in the intermediate latched position.

Figure 6 is a view similar to Figures 3 to 5 but showing the parts in the final locked position.

Figure 7 is a sectional view taken on line 7—7 of Figure 1 showing the cash removal door mounting.

Figure 8 is a side elevation of the coin funnel.

Referring now to Figure 1, the numeral 1 represents a cash box receiver which is fixed permanently to the vending machine and is formed of a back plate 3, substantially coextensive with the rear of the cash box 11, and which is provided at its upper, right-hand and lower edges with channels 5, 7 and 9 of U-shaped cross-section so that the cash box must be slid into position from the left (Fig. 1).

The cash box 11 comprises a rear wall 13, bottom wall 15, top wall 17, right end 19 and left end 21, the latter having affixed thereto a handle 23. The front wall 25 constitutes a door or cover and is provided with inwardly and downwardly bent ears 27 (Fig. 7) which hook over an upwardly turned flange 29 on the bottom 15.

The ends and top of the door are flanged inwardly as at 31 to fit over the ends 19 and 21 and top wall 17 so that no crevice will remain open through which a coin may be removed. The door projects downwardly beyond the flange 29 as shown at 33 to seal the lower end of the box.

A bracket 35 is fixed to and extends down from top 17 so as to be engaged by the bolt (not shown) of a key operated lock 37 which is fixed in the upper end of the door.

The upper wall 17 is slotted along the dotted line 39 (Fig. 4) and a short, rectangular tube 41 is fixed therein. The opening in the tube slidably receives and provides a passage for the shank 45 of a coin funnel 43 through the upper wall 17. The lower end of the shank is bevelled as at 47 to facilitate insertion of the funnel and to insure the ejection of coins therefrom.

A headed pivot pin 49 is riveted to the underneath side of the top 17 and pivotally carries the latching bar 51 which is in the form of a bell crank having arms 53 and 55. The lever lies close to the underside of top 17.

The arm 55 is provided with two projections 57 and 59, of which 57 serves as a latching means, which are adapted to project through slots 61 and 63 in the rear and right end walls 13 and 19 respectively of the box.

An abutment 65 is fixed to the inside of channel 7 adjacent slot 63 in position to be contacted by the projection 59.

The projection or latching means 57 is in alignment with a horizontal slot 67 in the back plate 3 of the receiving bracket 1 and since the box fits slidably but relatively snugly in said bracket, the projection in certain positions of the lever 51 serves to latch the box in place.

A bracket 69 is fixed to the wall 19 of the box and lies under the arm 55 of lever 51 to assist in supporting it in alignment with the slots 61, 63 and 67.

A spring 71 is attached to a depending pin 73 fixed in arm 53 and to a clip 75 fixed to the wall 13 of the box and serves to urge the bar 51 in a clockwise direction (Figs. 3 to 6).

One edge of the arm 53 is notched at 77 so as to clear the bracket 35.

A round stop pin 79 and a square, pawl locking pin 81 are fixed to the under side of the box top 17. The pin 79 is disposed near the corner formed by the walls 13 and 21, while pin 81 is disposed near the corner formed by wall 21 and the cover or door 25 and with its sides at an angle to said wall and cover.

Pivottally mounted on the underneath side of arm 53 by means of a pin 83 is a locking pawl 85 which is provided with a projection 87, and an intermediate and an outer tooth or step 89, 91 respectively.

A spring 93 is coiled about pin 83 and has one end bearing on a pin 95 depending from pawl 85 and the other bearing on a pin 97 depending from arm 53.

Operation

With the coin box empty and ready to insert in the vending machine, the locking lever 51 must occupy the Figure 3 position with the projection 87 of the locking pawl disposed between pin 79 and wall 13. The lever is thus free to rotate counterclockwise about pivot 49 and the projection 57 on arm 55 will enter the receiver 1, clearing the back plate 3 until it partially enters the slot 67 in said plate. The projection 59 extends through slot 63 so as to engage the abutment 65.

A firm push to the right (Figs. 3 and 4) will cause the lever to rotate counterclockwise to the Figure 4 position by reason of the pressure of abutment 65 on projection 59. The projection 57 is in full engagement in slot 67 in this position; the lever has moved out from under the guide tube 41 so that the coin funnel may be inserted and the projection 87 of pawl 85 has cleared the pin 79 and is now held with its edge against a corner of pin 81 by the spring 93. As shown in Figure 4, the shank 45 of the funnel blocks the return of the lever 51 to the Figure 3, 5 or 6 position and, consequently, prevents the withdrawal of the projection 57 from the slot 67 and the box is accordingly locked in the case.

After the coins have been collected and it is desired to remove the coin box, it is first necessary to remove the funnel; after which, pulling on the handle 23 will move the box to the left and spring 71 will rotate the lever clockwise to the Figure 5 position in which the pin 81 engages the step 91 of locking pawl 85. This is possible because the end 19 of the cash box has moved away from abutment 65.

In this position the projection 57 has not yet moved inwardly far enough to clear the back plate 3. However, it will be seen that the arm 53 has already closed the opening of tube 41. Since the pin 81 and step 91 are engaged, it is impossible, in any way, even at this stage, to work the arm in a reverse direction so as to open the box for the removal of money.

When the projection 57 has rotated far enough to clear the back plate 3, the lever 51 will thus be locked against reopening the coin opening.

The final stage is shown in Figure 6, in which the arm 53 is entirely over against the back plate of the box. In this position the pin 81 is engaged by the step 89 of pawl 85 and the projection 57 is clear of the back plate 3 so that the coin box can be removed. Again, however, the opening in tube 41 is closed by arm 53 and cannot be pried or worked open.

The trick of inserting a thin strip or scale between the arm 53 and the upper inside of the tube (Fig. 3) to prevent closure of the tube is foiled because the box would, under such conditions, still be held in the receiver until the Figure 5 position is passed; consequently, even if the arm is held open, the box cannot be inverted or otherwise manipulated to remove coins.

When the box is turned over to the accounting office, an authorized person possessing the key to lock 37 will open the lock, remove cover 25, remove the coins, reset the parts to the Figure 3 position, replace the cover and lock it. The box is then again ready for installation.

It is obvious that various changes may be made in the form, structure and arrangement of parts without departing from the spirit of the invention. Accordingly, applicant does not desire to be limited to the specific embodiment disclosed herein primarily for purposes of illustration; but instead, he desires protection falling fairly within the scope of the appended claims.

What I claim to be new and desire to protect by Letters Patent of the United States is:

1. In a coin collecting mechanism, the combination of a cash box, a receiver into which said box is insertable, latching means on the box adapted to be projected to engage said receiver, a coin opening in said box, a closure means for said opening having effective and ineffective positions, means interconnecting said latching means and closure to hold the former projected until after said closure means is in effective position, said latching means, when it is held projected, cooperating with said receiver to prevent withdrawal of the box therefrom, and an actuator in said box positioned to be moved by contact with said receiver when the box is inserted and connected to project said latching means and to move said closure to ineffective position.

2. In a coin collecting mechanism, the combination of a cash box, a receiver into which said box is insertable, latching means comprising a lever pivotally mounted in the box and having a projection adapted to be moved away from retracted position to engage the receiver, a coin opening in said box, said lever comprising a closure for said opening having effective and ineffective positions, means operable by the insertion of the box into the receiver for moving said closure means to ineffective position and for moving the projection away from its retracted position, and means operable upon the withdrawal of said box from said receiver for moving said closure means from ineffective to effective position and for retracting said projection, said projection, when held out of retracted position, cooperating with said receiver to prevent withdrawal of the box therefrom.

3. In a coin collecting mechanism, the combination of a cash box, a receiver into which said box is slidably movable in opposite directions, latching means comprising a lever pivotally mounted in the box and having a projection

adapted to be projected from the box to engage the receiver, a coin opening in said box, said lever comprising a closure for said opening having yieldably closed effective and ineffective positions, means for yieldably urging the closure to ineffective position, means operable by the insertion of the box into the receiver, including a second projection on said lever adapted to engage an abutment for moving said closure means from yieldably closed to ineffective position and to project said latching means, means operable upon the withdrawal of said box from said receiver for moving said closure means from ineffective to effective position and means for locking said closure in such effective position, said latching means, when it is held projected, cooperating with said receiver to prevent withdrawal of the box therefrom.

4. In a coin collecting mechanism, the combination of a cash box, a receiver into which said box is slidably movable in opposite directions, latching means comprising a lever pivotally mounted in the box and having a locking projection adapted to be projected from the box transversely of said directions to engage the receiver, a coin opening in said box, said lever comprising a closure for said opening having yieldably closed effective and ineffective positions, means operable by the insertion of the box into the receiver, including a second projection on said lever adapted to move substantially in the same directions as said box to engage an abutment for moving said closure means from yieldably closed to ineffective position and to project said latching means, means operable upon the withdrawal of said box from said receiver for moving said closure means from ineffective to effective position and means for locking said closure in such effective position, said latching means, when it is held projected, cooperating with said receiver to prevent withdrawal of the box therefrom.

5. In a coin collecting mechanism, the combination of a cash box, a receiver into which said box is insertable, a coin opening in said box, a closure having opened and closed positions with respect to said opening, a locking pawl on said closure having a locking tooth and having reset, tripped and locking positions, means urging said pawl toward locking position, a stop, a projection on said pawl adapted to engage said stop to hold the pawl in reset position while said closure is in closed position, means for yieldably holding said closure in closed position, a locking abutment for said pawl, means operable by the insertion of the box into the receiver for moving said closure to open position, thereby withdrawing said projection from said stop so that the pawl will be moved to tripped position against said abutment by said urging means, and means operable upon the withdrawal of said box from said receiver for moving said closure to closed position and the locking tooth of said pawl into locking position with said abutment to prevent reopening of said closure.

6. In a coin collecting mechanism, the com- 65

bination of a cash box, a receiver into which said box is insertable, a coin opening in said box, a closure having opened and closed positions with respect to said opening, a locking pawl on said closure having two locking teeth and having reset, tripped and multiple locking positions, means urging said pawl toward locking position, a stop, a projection on said pawl adapted to engage said stop to hold the pawl in reset position while said closure is in closed position, means for yieldably holding said closure in closed position, a locking abutment for said pawl, means operable by the insertion of the box into the receiver for moving said closure to open position, thereby withdrawing said projection from said stop so that the pawl will be moved to tripped position against said abutment by said urging means, and means operable upon the withdrawal of said box from said receiver for moving said closure to closed position and the locking teeth of said pawl serially into locking position with said abutment to prevent reopening of said closure.

7. In a coin collecting mechanism, the combination of a cash box, a receiver into which said box is insertable, latching means on the box adapted to be projected to engage said receiver, a coin opening in said box, a closure having opened and closed positions with respect to said opening, a locking pawl on said closure having a locking tooth and having reset, tripped and locking positions, means urging said pawl toward locking position, a stop, a projection on said pawl adapted to engage said stop to hold the pawl in reset position while said closure is in closed position, means for yieldably holding said closure in closed position, a locking abutment for said pawl, means operable by the insertion of the box into the receiver for moving said closure to open position, thereby withdrawing said projection from said stop so that the pawl will be moved to tripped position against said abutment by said urging means, means operable upon the withdrawal of said box from said receiver for moving said closure to closed position and the locking tooth of said pawl into locking position with said abutment to prevent reopening of said closure, and means for withdrawing said latching means from said receiver after said closure moves to closed position.

HAROLD E. FORESTER.
